Des. 235,459
Patented June 17, 1975

235,459

FIGURE RIDING TOY

Rouben T. Terzian and Kathy Dunn, Chicago, Ill., and
Laurie Jay Campbell, Erie, Pa., assignors to Marvin
Glass & Associates, Chicago, Ill.

Filed Apr. 18, 1974, Ser. No. 461,950

Term of patent 14 years

Int. Cl. D21—01

U.S. Cl. D34—15 AJ

Fig 2

Fig 3

FIG. 1 is a perspective view of a figure riding toy showing our new design;

FIG. 2 is a top plan view thereof;

FIG. 3 is a side elevational view thereof;

FIG. 4 is a front elevational view thereof;

FIG. 5 is a rear elevational view thereof; and

FIG. 6 is a bottom plan view thereof.

We claim:

The ornamental design for a figure riding toy, substantially as shown.
